UNITED STATES PATENT OFFICE.

JOHN HARTLAND RICHARDS AND BENJAMIN BELLINGHAM, OF SALTLEY, BIRMINGHAM, ENGLAND.

WORK-HOLDING APPLIANCE FOR USE IN CONNECTION WITH THE BORING OF BEARINGS AND THE LIKE.

1,284,456.

Specification of Letters Patent. Patented Nov. 12, 1918.

Application filed October 11, 1917. Serial No. 195,975.

To all whom it may concern:

Be it known that we, JOHN HARTLAND RICHARDS and BENJAMIN BELLINGHAM, subjects of the King of Great Britain, residing at Saltley, Birmingham, England, have invented certain new and useful Improvements in Work-Holding Appliances for Use in Connection with the Boring of Bearings and the like, of which the following is a

specification.

This invention relates to the boring of bearings and the like, but particularly bearings or brasses made in two halves. The object of the present invention is to provide means for holding the bearings or the like in position while being operated upon, which admits of the work being quickly removed and replaced, insures every bearing being bored true in relation to the longitudinal faces, minimizes the liability of errors occurring due to swarf and the like getting upon the faces of the work or upon the parts of the holder, and which comprises self-contained means for quickly and accurately setting the boring tools.

According to the present invention the work-holder consists of a detachable carrier open at the top or side for removal of the work and having self-contained means for fixing the work in position upon suitable faces or supports at opposite sides, said carrier being adapted to be removably supported within a jig or frame also open at the top or side to allow of the removal of the work from the holder.

Figure 1 of the accompanying drawings represents a longitudinal section through a work-holding appliance in accordance with this invention.

Fig. 2 represents an end view.

Fig. 3 is a vertical section on line α , Fig. 1, showing the work-clamping device.

Fig. 4 is a detail view showing one of the fastening devices for securing the work-holder in place within the jig.

Fig. 5 is a vertical view illustrating how the half-bearings can be bored in pairs.

Fig. 6 is a transverse section, and

Fig. 7 is an elevation illustrating a modification in which provision is made for adjusting the position of the bearing so that it can be bored either concentric or eccentric with respect to the outside diameter.

As shown in Figs. 1 to 4, the work-holding appliance consists of a main frame or jig 1 bolted to a suitable part of the lathe or boring machine and provided at one end with a boss or extension 2 carrying a central bearing bush 3 to receive and support the boring bar 4, which latter passes axially through the jig or frame. The said jig 1 is bored out cylindrically from the end opposite to that which supports the boring bar, and the upper part, for a length rather greater than the length of the bearing to be bored, is cut away at 5 to the horizontal center line, but leaving the end portions intact. This jig or frame 1 is arranged to receive within its interior a detachable work-holder 6 consisting of a substantially cylindrical body whose external diameter is equal to the internal diameter of the said jig or frame, into which it is adapted to be introduced through the open end. It is adapted to be secured therein by any suitable means, such as lever cams 7 turning about hinged or swinging pins so that they can be turned clear of the work-holder, as shown by dotted lines in Fig. 2. The work-holder 6 is bored out axially to a somewhat larger diameter than the boring bar 4, and the upper part is recessed or cut away between its ends to the horizontal center line of the jig, the cylindrical end parts 8, 9, engaging within the ends of the said jig. The half-bearing 10 is placed in the work-holder so that its flat longitudinal faces rest upon the flat longitudinal faces 11, 12, of the work-holder formed by cutting away the upper portion, these faces lying in a horizontal plane passing through the axes of the boring bar. To hold the bearing in position a radially adjustable stop-bar 13 is secured to one longitudinal face 11 of the work-holder, said stop-bar extending the full length of the bearing and serving as an abutment for the latter, while the opposite longitudinal face 12 of the work-holder carries a pair of curved brackets 14 supporting between them a longitudinal spindle 15 upon which are mounted two or more eccentric clamps or cams 16 provided with short operating levers 17. After the bearing 10 has been placed in position the eccentrics or cams 16 are operated so as to clamp the said bearing securely against the stop-bar 13 and force its flat longitudinal faces against the

faces 11, 12, of the work-holder 6. The inner end of the said work-holder is preferably coned at 18 to engage within an internally tapered recess in the corresponding end of the 5 jig. By means of the eccentric clamps 16 the bearings can be quickly removed and replaced by others through the open top of the jig, and thus the true boring of all bearings relatively to the longitudinal faces is insured.

When a bearing of a different size is to be bored the work-holder is removed endwise from the jig and replaced by another which is suitable for the said bearing.

15 The boring bar 4 preferably carries two radially arranged tools 19 disposed diametrically opposite to one another, but longitudinally separated, so that the tools are brought into action successively, the one tool 20 commencing a cut as the other moves out of the half bearing. The tools are adjustable by means of screw plugs 20 engaging with their inner ends, and they may be fixed by set-screws. To facilitate the setting and adjustment of the tools, the jig or main frame 25 1 carries a micrometer gage 21 which projects radially into the recessed interior 22, so that by bringing the tools opposite to the gage the correct setting can be readily determined.

When the half-bearings are to be bored in pairs the lower portion of the work-holder 6, as shown in Fig. 5, may be recessed to receive the bottom half 23 of the bearing 35 which may be held in place against the upper half 10 by one or more wedges 24, or by other suitable means, the said upper half 10 being provided with lugs 25 flush with the flat longitudinal faces and which engage 40 with the flat faces 11, 12, of the work-holder.

The jig or main frame may either be fed longitudinally of the boring bar held stationary, or the boring bar may be fed forward and the jig secured to a fixed part of the lathe or boring machine.

To admit of the position of the bearing being adjusted relatively to the boring bar, so that the inner surface may be bored either 50 concentric or eccentric with respect to the outside diameter, as desired, the arrangement represented in Figs 6 and 7 may be adopted. Thus, applied to the flat faces 11, 12, of the work-holder 6 is a bracket or 55 carrier 26 having interior ledges 27 against which the bearing 10 is clamped by a screw 28, and provided with external flanges 29 laterally adjustable within guide channels 30 and engaged by set-screws 31 extending 60 into said channels. The apparatus illustrated in Figs. 6 and 7 is shown as being arranged vertically for a vertical boring-bar. Likewise the apparatus shown in Figs. 1 to 3 may be arranged vertically instead of 65 horizontally.

Having fully described our invention, what we desire to claim and secure by Letters Patent is:—

1. In a work-holding appliance for use in connection with the boring of bearings and the like, the combination with a fixed open frame having a socket in one end and an opening in the other end, of a detachable one-piece work-holder having bearing surfaces for the work, said work-holder being formed at opposite ends so as to be endwise insertible in and removable from the fixed frame through the opening in the one end, means carried by and self-contained with the removable work-holder for fixing the work to the latter, said work-fixing means being included within the contour of the opening in the one end of the fixed frame so as to be removable therethrough with the work-holder, and means independent of the work-fixing means for the purpose of securing the work-holder within the fixed frame. 75

2. In a work-holding appliance for use in connection with the boring of bearings and the like, the combination with a fixed frame with an opening and also having a recess in one end and an opening in the other end, of a detachable one-piece work-holder of enclosing cylindrical form adapted to be inserted endwise through the opening in one 90 end of the fixed frame so that its one extremity engages within the recess in the other end of the said frame and abuts against an interior part of the frame, said work-holder having an opening corresponding in location to 95 the position of the opening in the fixed frame to admit of the removal of the work in a radial direction, means wholly carried by and self-contained with the removable work-holder for fixing the work to the latter, said work-fixing means being included within the contour of the opening in the one end of the fixed frame, and means independent of the work-fixing means for the purpose of securing the work-holder within the fixed frame. 100

3. An appliance for boring bearings and the like comprising a boring bar, a fixed frame having at one end an axial bearing for said boring bar and an internal socket concentric with said bearing and at the other 115 end an opening, a detachable one-piece work-holder endwise insertible in and removable from the fixed frame through the opening in the end thereof, means wholly carried by and self-contained with the removable 120 work-holder for fixing the work to the latter, said work-fixing means being included within the contour of the opening in the end of the frame, and means independent of the work-fixing means for the purpose of securing the work-holder within the fixed frame. 125

4. In a work-holding appliance for use in connection with the boring of bearings and the like, the combination with an open frame, a detachable one-piece work-holder 130

- of inclosing cylindrical form having work-supporting faces at opposite sides and insertible endwise within the frame, an adjustable stop-bar extending longitudinally 5 upon one of said work-supporting faces, means carried wholly upon the other work-supporting face for fixing the work in position against said stop-bar, and means independent of the work-fixing means for securing 10 the work-holder within the fixed frame.
5. A work-holding appliance for use in connection with the boring of bearings and the like comprising an open frame, a boring-bar supported by and movable through 15 the frame, said frame being bored out cylindrically and being cut away to the axial plane between end portions, a work-holder of inclosing cylindrical form detachably supported within the interior of the frame and removable endwise, said work-holder 20 being bored out to receive the boring-bar and being cut away, between its ends, to the axial plane, forming two flat longitudinal faces upon which the work is adapted to be placed, a stop member upon one face, means 25 carried wholly upon the other face for fixing the work in position against the stop device, and means independent of the work-fixing means for securing the work-holder within the fixed frame. 30

In testimony whereof we have hereunto set our hands in presence of two subscribing witnesses.
